CLAIM

I claim the ornamental design for a cooking pot with lid, as shown and described.

DESCRIPTION

FIG. 1 is a front view of the cooking pot with lid showing my new design, with the lid shown removed for ease of illustration.

FIG. 2 is a side view thereof.

FIG. 3 is a top view thereof.

FIG. 4 is a bottom view thereof.

FIG. 5 is a perspective view thereof; and,

FIG. 6 is a cross-sectional view of the cooking pot taken in the direction of line 6-6 of FIG. 2.

1 Claim, 6 Drawing Sheets
